(57) **CLAIM**

The ornamental design for a diaper changing station, as shown and described.

DESCRIPTION

FIG. 1 is a perspective view of a diaper changing station showing our new design;

FIG. 2 is a top plan view thereof; and,

FIG. 3 is a left side elevational view thereof, the right side being a mirror image of that shown.

Portions of the article shown in broken lines are for illustrative purposes only and form no part of the claimed design.
